Carl Schraysshuen, Providence, R. I.

Application April 16, 1945, Serial No. 119,041

Term of patent 14 years

(Cl. D45—1)

To all whom it may concern:

Be it known that I, Carl Schraysshuen, a citizen of the United States, residing at Providence, in the county of Providence and State of Rhode Island, have invented a new, original, and ornamental Design for Bracelet Link, of which the following is a specification, reference being had to the accompanying drawing, constituting a part thereof.

Fig. 1 is a plan view of a bracelet link showing my new design.

Fig. 2 is a side view thereof.

I claim:

The ornamental design for a bracelet link, substantially as shown.

CARL SCHRAYSSHUEN.
